United States Patent Office.

JAMES S. CONLIN, OF NEW YORK, N. Y.

Letters Patent No. 78,929, dated June 16, 1868.

SHOOTING-GALLERY.

The Schedule referred to in these Letters Patent and making part of the same.

TO ALL WHOM IT MAY CONCERN:

Be it known that I, JAMES S. CONLIN, of the city, county, and State of New York, have invented a new and useful Improvement in Shooting-Galleries; and I do hereby declare that the following is a full, clear, and exact description thereof, which will enable those skilled in the art to make and use the same, reference being had to the accompanying drawings, forming part of this specification, in which—

Figure 1 is a vertical longitudinal section of my improved shooting-gallery, taken through the line Y Y, fig. 3.

Figure 2 is a partial front view of the same.

Figure 3 is a horizontal section of the same, taken through the line X X, fig. 1.

Figure 4 is a vertical cross-section of the same, taken through the line x x, figs. 1 and 2.

Figure 5 is a vertical cross-section of the same, taken through the line y y, figs. 1 and 2.

Figure 6 is a vertical cross-section of the same, taken through the line z z, figs. 1 and 2.

Figure 7 is a vertical cross-section of the same, taken through the line x' x', figs. 1 and 2.

Figure 8 is a detail view of the rifle-target enlarged.

Similar letters of reference indicate corresponding parts.

My invention has for its object to improve the construction of shooting-galleries so as to make them convenient for use, easily operated, and entirely safe; and it consists in the construction, combination, and arrangement of the various parts, as hereinafter more fully described.

The gallery is divided into two parts by a longitudinal partition, A, or, in other words, a side gallery or passage-way, B, is formed along one side of the main gallery, running its entire length, so that the attendant can conveniently pass along it, and enter the main gallery at any point where his services may be required.

C is the front of the gallery, through which, at a convenient height, is formed an opening, D, in which the arm is inserted when loaded, and from which it is not removed until fired, the arm never being capped until its muzzle has been passed through said opening, thus guarding bystanders from any danger of being injured by an accidental discharge of the arm.

E is the first compartment of the gallery, which is made short, being only of sufficient length to allow the person shooting to see the sights of the arm clearly, light for this purpose entering through a sky-light or window, F, placed in the roof or cover of the gallery, as shown in fig. 4.

The next compartment of the gallery is a low and narrow tunnel, G, the walls of which should be plated with iron, or otherwise strengthened, and which is made so narrow that it will be impossible for the arm to be turned at such an angle with the walls of said tunnel that a ball by any chance could pass through said walls, but would necessarily pass through said tunnel into the next compartment H.

The compartment H is made of such a length that the partition I which forms the further end of said compartment may be at a suitable distance from the front, C, to serve as a support for the pistol-target J.

The pistol-target J is a door hinged in a doorway in the partition I, and which is formed of iron, or is so heavily plated with iron as to be able to resist the force of any pistol or rifle-ball.

The part of the target which can be seen through the tunnel G is painted white, so that the marks of the balls can be easily seen from the front of the gallery.

The bull's-eye of the target J is a round hole through its centre, as shown in dotted lines in fig. 5.

K is a drop-plate or block of iron, made of sufficient strength to resist the force of any pistol or rifle-ball.

The drop K is pivoted to the rear side of the target J, and is so constructed and balanced by a suspended weight or otherwise, that whenever a ball hits the bull's-eye, or enters the hole through the target J and strikes the drop K, it will fall.

To the upper edge of the drop K is attached a cord, b, which passes through the partition A, is led by means of guide-pulleys to the front, C, of the gallery, where it is connected with a gong or other bell, L, so that as the drop K falls, it will ring the said bell, and thus unmistakably signal the fact that the bull's-eye has been hit.

The drop K is again raised by the attendant at the front of the gallery, by means of the cord or wire 7, one end of which is attached to the upper end of the said drop K, which passes through the partition A, and is led by guide-pulleys to the front, C, of the gallery, where it terminates in a tassel or other handle, in such a position that it may be conveniently reached and operated by the attendant.

Access to the chamber H, to attend to the target J, is obtained through the door M, in the partition A.

The door M is secured, when closed, by a hook, spring-lock, or other convenient means, is provided with a suspended weight, N, is so arranged that as soon as it is unfastened it will swing inward, completely covering the farther end of the tunnel G, and is plated with iron, or otherwise made so thick and heavy as to be ball-proof, so that should a pistol or rifle be discharged while the attendant is in the compartment H, it will be impossible for the ball to hit him.

The target J is drawn and held closed by a cord, 5, one end of which is attached to said target, which passes through the partition A, and is led to the front, C, of the gallery by guide-pulleys, where it is secured by means of a belaying-cleat, or other convenient means.

The target J is also provided with a suspended weight, O; which, as soon as the cord or wire 5 is unfastened, draws the said target back against the partition A out of sight, and out of the range of the balls.

The target J is lighted, when in use, by means of the trap-door P, formed in the roof or cover of the gallery, directly in front of the partition I, as shown in dotted lines in fig. 5, which is kept open when the gallery is used for pistol-practice, to light the target J, and is kept closed when the gallery is used for rifle-practice, so that the middle part of said gallery may be kept dark.

The next compartment Q is made long, and the partition R, that forms its further end, is made with an oblong opening, S, through it.

T is a heavy iron plate, perfectly ball-proof, sliding in grooves upon the rear side of the partition R, and connected with the door U in the partition A, and which opens outward into the passage-way B by a cord, V, so that when the door U is opened to admit the attendant into the compartment W, the plate T will be raised, covering the opening S in the partition R, so that it will be impossible for the attendant to be shot, even should a rifle be accidentally discharged while he is in said compartment W.

The door U when closed is fastened by a hook, spring-lock, or other fastening, and is provided with a suspended weight, X, which, as soon as the door U is unfastened, swings it open and raises the ball-proof plate T, so that it is impossible for the attendant to enter the compartment W, without, in so doing, securing himself against being accidentally shot.

The compartment W is made short, allowing only space for the attendant to conveniently enter and attend to the target, and is lighted through a sky-light or window, Y, in the cover or roof of the gallery, and which is placed directly in front of the partition Z, which forms the rear end of the compartment W; and supports the rifle-target A'.

By this construction only the middle part of the rifle-target can be seen from the front of the gallery through the oblong opening S.

The effect of the partition R being, (and this is one of the main purposes of said partition,) to shut off the light almost entirely from the middle part or chamber Q of the gallery, while at the same time bringing the middle part of the rifle-target into strong relief.

The rifle-target A' is a heavy iron plate, completely ball-proof, and securely attached to the partition Z, and the bull's-eye is a hole through its centre, shown in dotted lines in figs. 3 and 7.

In the rear of the target A' is pivoted a ball-proof block, B', which, when raised, covers the bull's-eye of the target A', and which is so balanced that when struck by the ball it may fall down.

To the upper end of the block B' is attached a cord, 1, which passes through the partition A, and is led by means of guide-pulleys to the front of the gallery, where it is connected with a bell, C', so that whenever the bull's-eye is hit it may be at once signalled by the ringing of the bell C'.

The block B' is again raised by means of the cord 2, one end of which is attached to the upper end of the block B', which passes through the partition A, and is led by guide-pulleys to the front of the gallery, so that the attendant at the front of the gallery can conveniently raise said block.

D' is a shaft, which passes through the partition Z below the target A', and which has attached to its forward end a block or plate, E', having three or more arms projecting from it, having heads or other fanciful designs formed upon their ends, which, when the bull's-eye has been hit, revolves one or the other of its arms up in front of said bull's-eye, and which, when the block B' is again raised, revolves the said arms again out of sight.

To the rear end of the shaft D' is attached or upon it is formed a three or more toothed ratchet-wheel, F', the pawl G' of which is connected with the block B' by a cord, H', so that when the said block B' falls, it may lift the pawl G' away from the ratchet-wheel F', and allow the shaft D' and armed plate or block E' to be revolved by the weight I', which is connected with the said shaft D' by a cord, J', wound around said shaft.

K' is a bent arm, attached to the block B', which, when the block B' falls, passes through a slot in the partition Z, to serve as a stop to detain the armed plate or block E' in position for one of its arms to cover the bull's-eye of the target A'.

L' is a short compartment between the partition Z and the rear end M' of the gallery, into which access may be had, when required, through a narrow door, N', in the partition A.

O' is a bell, placed near the door U, near which an attendant usually sits or stands, and which is connected with the front of the gallery by the cord 3, so that the attendant at the front of the gallery can readily notify the said attendant when it is desired that he should enter the compartment W to attend to the target A', or for any other purpose.

As soon as the attendant has retired from the compartment W, and fastened the door U, he pulls the cord 4, which rings the bell P', at the front of the gallery, and thus signals to the attendant at that point that the rear end of the gallery is again all-right.

Q' is a rest, which moves up and down vertically, through a hole in the platform R' of the compartment E, and the upper end of which is notched to receive the barrel of the gun.

To the lower end of the rest Q' is attached one end of the cord S', which passes over a guide-pulley attached to the under side of the platform R', and its other end is wound around and attached to the horizontal shaft T', the forward end of which projects out through the front, C, of the gallery, and has a crank, U', attached to it, by means of which the said shaft is revolved to raise the rest Q' to any desired height.

The shaft T' is held in any position to which it may be revolved by the lever-pawl V', which takes hold of a ratchet-wheel, W', attached to or formed upon the shaft T', as shown in fig. 1.

X' is a rod, passing down through the platform R', with its lower end resting upon the rear end of the lever-pawl V', so that, by slightly pressing upon the projecting end of the said rod X', the pawl V' may be raised from the ratchet-wheel W', allowing the rest Q', by its own weight, to run down out of the way, and entirely out of sight.

It should be observed that the bells L P' C' O' are all different, so that the sound of one cannot be mistaken for the sound of the other, each one communicating its signal by its own peculiar sound.

I claim as new, and desire to secure by Letters Patent—

1. The weighted ball-proof door M, so arranged between the tunnel G and pistol-target J, that when said door is unfastened, it will swing open to protect the attendant at the target from balls inadvertently discharged, substantially as set forth.

2. Forming the targets J and A' with holes through their centres, for the bull's-eye, and with drop-plates or blocks K and B', which are connected with the front of the gallery by means of cords and bells, substantially as and for the purposes herein shown and described.

3. Pivoting or hinging the pistol-target J to the partition I, so that it may be swung back out of the way, substantially as herein shown and described, and for the purpose set forth.

4. The pistol-target J, when connected to the front of the gallery by means of a cord, 7, so that it may be swung to its place from the said front of the gallery, substantially as set forth.

5. The arrangement, in-front of the rifle-target A', of the partition R, formed with an opening, S, and provided with a sliding ball-proof plate, T, which latter is so connected, by means of a cord, V, to the door U, that when said door is opened, the opening S is covered by the plate T, to protect the attendant, substantially as described.

6. The combination of the weighted door U and sliding ball-proof plate T with each other, and with the partition R and rifle-target A', substantially as herein shown and described, and for the purpose set forth.

7. The combination of the plate or block E', having three or more arms projecting from it, shaft D', ratchet-wheel F', weight I', and stop-arm K', with each other, with the drop-plate or block B' and target A', substantially as herein shown and described, and for the purpose set forth.

8. The combination of the adjustable rest Q', shaft T', ratchet-wheel W', pawl V', and rod X', with each other, and with the forward part of the gallery, substantially as herein shown and described, and for the purpose set forth.

9. An improved shooting-gallery, constructed and arranged substantially as herein shown and described, and for the purpose set forth.
